UNITED STATES PATENT OFFICE

2,435,864

EXERCISING DEVICE

Edward John Adams, Kent, Ohio

Application June 13, 1944, Serial No. 540,017

1 Claim. (Cl. 272—78)

1

The present invention relates to new and useful improvements in exercising devices, and has for its primary object to provide, in a manner as hereinafter set forth, a device of this character comprising unique means for developing the shoulders, legs, arms and abdomen, improving timing, promoting mental and physical agility, et cetera.

Another very important object of the invention is to provide an exercising device of the aforementioned character comprising novel means for supporting a punching bag for swinging movement in a horizontal plane.

Still another important object of the invention is to provide an exercising device of the character described wherein the aforementioned punching bag may be readily adjusted vertically as desired.

Other objects of the invention are to provide an exercising device which will be comparatively simple in construction, strong, durable, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of an exercising device constructed in accordance with the present invention.

Figure 2 is a top plan view thereof.

Figure 3 is a longitudinal sectional view, taken substantially on the line 3—3 of Figure 2.

Figure 4 is an elevational view of the outer portion of the swinging arm with the bag thereon, parts being omitted.

Referring now to the drawings in detail, it will be seen that the embodiment of the invention which has been illustrated comprises a smooth, tubular metallic post 1 of suitable height and diameter. The post 1 is mounted on a base 2 which, in turn, is secured on the floor by suitable fastening elements 3.

Journalized on the post 1 is a vertically adjustable bearing 4. A removable pin 5 is insertible selectively in spaced, staggered openings 6 in the post 1 for supporting the bearing 4 in adjusted position. Projecting horizontally from the bearing 4 is a telescopically adjustable arm 7. As illustrated to advantage in Figure 3 of the drawings, the arm 7 includes male and female sections 8 and 9, respectively.

A punching bag 10 is mounted horizontally on the outer end of the arm 7 in longitudinal alignment therewith. Toward this end, the bag 10 is provided, on its inner end, with a flexible loop

11 having mounted therein a metallic ring 12. A hook 13 on the outer end of the arm 7 is engaged in the ring 12 for detachably connecting the bag 10 to said arm.

5 Threadedly mounted for adjustment on the outer end portion of the arm 7 is a substantially cone-shaped or bell-shaped fitting 14 which is engageable over the inner end portion of the bag 10, said fitting also enclosing and concealing the elements 11, 12 and 13. The fitting 14 is provided with a cushioning cover 15 of sponge rubber. A lock nut 16 secures the fitting 14 in adjusted position on the arm 7.

10 It is thought that the manner in which the device functions will be readily apparent from a consideration of the foregoing. Briefly, the bag 10 is punched back and forth in a horizontal plane with both fists or, if desired, said bag may be caused to swing in a complete circle around the post 1. In addition to permitting the exercising of virtually all parts of the body, the device may also be used for training by boxers and other athletes. By simply inserting the pin 5 in the correct opening 6, the bag 10 may be adjusted to the desired elevation to suit the individual. Set screws 17 secure the section 8 of the arm 7 in adjusted position in the section 9.

15 20 25

It is believed that the many advantages of an exercising device constructed in accordance with the present invention will be readily understood, and although a preferred embodiment of said device is as illustrated and described, it is to be understood that changes in the details of construction and in the combination and arrangement of parts may be resorted to which will fall within the scope of the invention as claimed.

What is claimed is:

30 An exercising device comprising a post, an arm mounted for horizontal swinging movement on said post, a hook on the free end of said arm, a punching bag loosely and detachably connected to said hook, and a substantially bell-shaped fitting threadedly mounted on the arm and engageable over the inner portion of the punching bag for maintaining said bag in a horizontal position in longitudinal alignment with the arm.

EDWARD JOHN ADAMS.
